UNITED STATES PATENT OFFICE.

WALTER E. BENNETT, OF HOUSTON, TEXAS.

FUEL-ECONOMIZER.

1,153,994.

Specification of Letters Patent. Patented Sept. 21, 1915.

Application filed August 2, 1913. Serial No. 782,567.

To all whom it may concern:

Be it known that I, WALTER E. BENNETT, a citizen of the United States, residing at Houston, in the county of Harris and State 5 of Texas, have invented certain new and useful Improvements in Fuel-Economizers, of which the following is a specification.

This invention relates to new and useful improvements in a fuel economizer.

10 The object of the invention is to provide a device of the character described whereby the unconsumed carbon and gases given off from the ordinary stove or oven or other consuming furnace may be reconveyed to 15 the combustion chamber and utilized.

It is a well known fact that in the consumption of such fuels as coal, from seventy-five to ninety per cent. of the fuel passes off in the form of unconsumed gas and smoke 20 and ordinarily is wasted.

It is the object of this invention to recon- 25 vert this gas and smoke into combustible form and reconvey it into the furnace chamber where it is completely consumed, thus 30 completely utilizing all of the fuel.

With the above and other objects in view, the invention has particular relation to cer- 35 tain novel features of construction, and ar- 40 rangement of parts, an example of which is given in this specification and illustrated in 45 the accompanying drawings, wherein—

Figure 1 is a plan view of the economizer. Fig. 2 is a side elevation thereof. Fig. 3 is an end view of the nozzle employed in 50 connection with the device, and Fig. 4 is a side elevation of said nozzle.

Referring now more particularly to the drawings, wherein like numerals of reference designate similar parts in each of the 55 figures, the numeral 1 refers to the ordinary stove in which coal or other fuel is con- sumed in the usual manner, said stove hav- 60 ing the removable ash pan 1' in the lower portion thereof to receive the final products of combustion. From this stove leads the pipe 2 which communicates with a coiled pipe 3 which is surrounded by and inclosed in the tank 4 which is at all times kept full of cold water. The smoke and gases given 65 off from the burning fuel in the stove 1 passes through the pipe 2 and the coil 3 and is cooled in said coil and passes therefrom through the pipe 5 which communicates with and leads from said coil 3. Suction is 70 created through these pipes and coil by means of the suction fan 6 which is driven

by the motor 7 and the object of cooling the gases by passing them through the coil 3 is to prevent the excessive heating and pos- 60 sible melting of the fan 6. The pipe 5 ex- tends down into a water tank 8 which is filled practically full of water so as to im- merse the lower free end of the pipe 5. A tank 9 is provided which is partly filled with water and kerosene or other similar 65 oil is then poured into said tank upon said water until the tank is almost filled.

Leading from the tank 8 is a pipe 10 which extends down into the tank 9 and whose lower end is immersed in the water 70 therein and leading from the tank 9 is a pipe 11 which extends into the combustion chamber of the stove or furnace. The end of said pipe extending into said stove has a nozzle 12 having a plurality of discharge 75 orifices through which the gas is discharged into the furnace where combustion of said gas takes place. It is obvious that as the unconsumed gas passes through the water in tank 8, it will be filtered and all ashes 80 and cinder and other foreign matter will remain in said water and also the possi- bility of any fire passing into the tank 9 will be cut off. The fan 6 creates a suffi- 85 cient draft for the stove 1 and also forces the gas under pressure through the tanks 8 and 9. As the gas passes from the pipe 10 it passes up through the oil in the tank 9 and is enriched thereby and thereby becomes more combustible thus insuring a better 90 flame and more complete combustion.

By the use of this economizer, all smoke is eliminated and all unconsumed carbon which passes from the burning fuel is uti- 95 lized.

What I claim is:—

1. In a fuel economizer, the combination with a combustion chamber, of a gas pipe leading therefrom, a cooling chamber through which said pipe passes, a current 100 generator communicating with the pipe for creating a suction therethrough, two other tanks, the former of which is provided to contain water and the latter of which is provided to contain water and fuel oil, said 105 pipe extending into one of said two tanks and its end being immersed in the water contained therein, a pipe extending from said last mentioned tank and extending down into the other of said two tanks and having its end immersed in the water therein, a discharge pipe leading from said last 110

- mentioned tank into the combustion chamber and discharging the gas conveyed thereby into said chamber, and a nozzle carried by the inner end of said discharge pipe.
- 5 2. In a fuel economizer, the combination with a combustion chamber, of a tank provided to contain water, a fluid conduit leading from said combustion chamber and extending down into said tank and into the water contained therein, a chamber in which a section of said conduit is coiled provided to contain water for cooling the gas passing through the conduit, a means for creating a suction through said conduit, a fuel tank, a fluid conduit leading from the first mentioned tank and extending down into said fuel tank, a fluid conduit leading from said fuel tank and discharging into the combustion chamber and a discharge nozzle with- 10 in the combustion chamber carried by the discharge end of the last mentioned fluid conduit.
- 15 3. In a fuel economizer, the combination with a combustion chamber, of a water containing tank, a fluid conduit leading from
- 20
- 25

said combustion chamber and extending down into said tank and into the water contained therein, a section of said conduit being coiled and a chamber inclosing said coiled section and provided to contain water for cooling said coil, a suction fan communicating with said conduit and creating a current therethrough, a fuel tank, a fluid conduit leading from the first mentioned tank and extending through into said fuel tank, a fluid conduit leading from said fuel tank and discharging into the combustion chamber, a nozzle carried by the discharge end of said conduit, said nozzle having a plurality of discharge orifices through which the fuel is discharged into the combustion chamber.

In testimony whereof I have signed my name to this specification in the presence of two subscribing witnesses.

WALTER E. BENNETT.
